(57) **CLAIM**

The ornamental design for a nozzle, as shown and described.

DESCRIPTION

FIG. 1 is a top perspective view of a nozzle showing my new design;

FIG. 2 is a bottom perspective view thereof;

FIG. 3 is a front elevational view thereof with the rear view, right side elevational view, and left side elevational view all being the same as the front elevational view;

FIG. 4 is a cross-sectional view taken along line 4—4 of FIG. 3;

FIG. 5 is a top view thereof; and,

FIG. 6 is a bottom view thereof.
